UNITED STATES PATENT OFFICE

161,559

DISPLAY RACK

John R. Warp, Chicago, Ill., assignor to Flex-O-Glass, Inc., Chicago, Ill., a corporation of Illinois

Application February 8, 1949, Serial No. 746

Term of patent 14 years

(Cl. D80—9)

To all whom it may concern:

Be it known that I, John R. Warp, a citizen of the United States, residing at Chicago, in the county of Cook, and State of Illinois, have invented a new, original, and ornamental Design for a Display Rack, of which the following is a specification, reference being had to the accompanying drawing, forming a part hereof.

In the drawing:

Fig. 1 is a front elevational view of a display rack, embodying my new design.

Fig. 2 is an enlarged end elevational view taken from the right in Fig. 1.

Fig. 3 is a horizontal sectional view on a reduced scale taken approximately along the line 3—3 of Fig. 2.

The dominant features of my design reside in the portion shown in full lines.

I claim:

The ornamental design for a display rack, as shown and described.

JOHN R. WARP.
